SLED OR BOAT

Benjamin F. Brasch, Parma, Ohio, assignor to Blazon, Inc., Akron, Ohio, a corporation of Ohio
Filed Mar. 30, 1960, Ser. No. 18,679
9 Claims. (Cl. 9—310)

The present invention relates to a passenger carrying vehicle which is slideably movable over water, snow, or ice.

Heretofore, sleds or toboggans of the type having a main central ski and parallel outboard skis or runners have been known. See, for example, U.S. Patent 386,414—Pusey. One disadvantage of such arrangement has been that it necessitates an excessive sidewise tilt of vehicle to obtain a relatively small amount of turn, or sometimes tilting merely puts the sled on two runners with no turning action at all.

It is an object of the present invention to provide simple and inexpensive means for overcoming the above mentioned difficulties.

Another object of the invention is to provide a novel sled or toboggan readily maneuvered by mere lateral shifting of the load carried thereby.

Another object of the invention is to provide a readily controllable while safe and practical central runner sled having a minimum number of parts (and no moving parts) and consequent low cost of manufacture.

Another object of the invention is to provide a sturdy vehicle of one piece construction, suitable for use by one or two persons in either an upright sitting position or lying face downward.

Broadly, in accordance with one aspect of the present invention, I meet these and other objects by providing a sled having a main central ski and two oppositely arranged outboard drag devices of less effective depth. In accordance with a preferred embodiment, the drag devices are skis each affixed at an angle so that a plane through the longitudinal center line of each outboard ski, if extended, will intersect a plane through the vehicle longitudinal center line, and thus through the central ski.

This provides an entirely different turning principle than those heretofore known because the outboard device, which is activated by platform tilting, provides a substantial force when it engages a sliding medium thereby creating a substantial turning moment without necessitating excessive tilt of the vehicle. Thus a simpler, more controllable ski sled is provided.

Other objects and advantages will become apparent and the invention may be better understood from consideration of the following description taken in connection with the accompanying drawing, in which:

FIG. 1 is a top view of a device constructed in accordance with the invention;

FIG. 2 is a side elevation of the device shown in FIG. 1;

FIG. 3 is a cross-sectional view on the line 3—3 of FIG. 2;

FIG. 4 is a cross-sectional view on the line 4—4 of FIG. 2;

FIG. 5 is an upwardly viewed corner portion illustrating a modification;

FIG. 6 is a diagrammatic top or bottom view including a force diagram illustrating operation of a device as in FIG. 1 or 7;

FIG. 7 is a perspective view of an alternate construction;

FIG. 8 is an exploded view of a ski useful, for example, as shown at 16 in FIGS. 1, 2 and 4.

In FIGS. 1—4, I have shown a pan-like central runner 10 which may be made of aluminum or other material. If desired, the pan top may be flanged at 11 to provide

2

ease of attachment of the pan as to a platform 12, and flange 11 may be interrupted at 13 to provide an additional flange to receive a hollow cantilever beam 14 to support the platform. The central runner 10 may be affixed to the platform 12 as by bolts (not shown).

The platform 12, which could be one molded piece but which is shown in FIGS. 1—4 as an assembly of two slightly angled sheets conveniently of ply-wood, has the overall pattern of a delta wing and at either side of a normally vertical plane or center line 15 drag devices such as oppositely angled skis 16 are affixed beneath the platform at outboard corners thereof.

At the front of the vehicle, a rigidly mounted handle 17 may be provided just forward of a mast hole 18 with said hole located above a mast step plate 19 for receiving a mast for sailing when that is desired.

For maximum maneuverability, while at the same time preventing skidding, the pan or shell forming the central runner 10 is bottom edge rounded as at 21, 22, adjacent the front or bow of the vehicle (see FIG. 3) and may also have a small center runner 23 (which may be just a protrusion of the pan as stamped), while toward the rear and adjacent the outrigger skis 16, these curves have individually coalesced into sharp points 24, 25, located on either side of an upwardly arcuate bottom 26 of the pan 10 (see FIG. 4).

During the operation with the combined main central runner rounded edges fore and small central runner sharp edges fore (as seen in FIG. 3) and the main central runner sharp edges aft (FIG. 4), sharp edges front and back prevent skids on ice but without restricting turns because any sharp edge of the small central forward portion of the central ski will be removed from the sliding medium during turns, the central sharp edge becoming ineffective as the vehicle is rolled over on rounded edge 21 or 22.

If desired, hand holes (as for holding for belly-slammimg) may be provided in the platform at 31, 32 and when the occupant is sitting down facing the front, he may use additional hand holes 33, 34 and, where possible, a hand hole such as 33 is protected from the snow, ice, water, etc. by structural parts such as 14, 16.

In a modification as shown in FIG. 5, the platform assembly 12 is provided with oppositely located drag devices one of which is shown at 36. With this embodiment, each drag device takes the form of a simple bracket fastened to the bottom of the platform 12 assembly with the engaging surface of said bracket fashioned to provide a substantial drag force such as by corrugations 37 preferably with the corrugations at an angle with respect to a line running fore and aft of the vehicle, and preferably, also, with the bottom ends of the brackets (that is, the bottoms of the corrugations if any) angled downward with respect to the platform portion, for example so that a plane in which they fall will intersect a plane containing the bottom of the central runner, so as to provide maximum area of drag device contact with sliding medium during turning as is the case for the arrangement of FIGS. 1—4 and 7, also, and with such an arrangement it is not necessary to "angle" the bracket itself with respect to a line running fore and aft.

If the vehicle is to be used on water, the end of members 10 and 14 (see FIGS. 1—4) may be enclosed and seams to be relied upon for buoyancy made water tight so that the vehicle will float when the vehicle is stationary, or when it is being brought up to planing speed as by initial towing with a motor boat. However, if the vehicle is to be used only on snow and ice, this is not essential and an end such as the end 38 of member 14 in FIG. 2 may be left open to reduce weight.

FIG. 6 includes a force diagram from which it is seen that with forward motion in the direction of arrow 61,

as soon as the sled, for example of FIGS. 1-4, is laterally tilted to engage one drag device 16, a drag force represented by the arrow 62 resolves into a perpendicular component 63 and a drag ski angle component represented by the arrow 64 both of which will cause turning with respect to an assumed center of gravity (of sled plus load) at a point 65.

In the arrangement of FIG. 7 the entire sled is formed as one drawn, stamped or molded piece as of metal or plastic, with indentations and convolutions of this piece forming a "pan" type central runner 70 convex (viewed from the bottom) in front and concave (from the bottom) in back, a platform 72, transverse stiffening (cantilever) corrugations 74, and angled outboard runners 76 which are again assumed raised (as to bottom surfaces) with respect to central runner (bottom surfaces).

With a one piece arrangement as in FIG. 7, it is not necessary to separately attach drag devices to platform, but where separate elements are used, as in FIGS. 1 and 2, they can easily be attached by heat fusion, or bolts, rivets and the like, particularly if the skis and other under parts are provided with top flanges as indicated by the double lines at each end of each ski 16 in FIG. 1. In FIG. 2, it appears that ski 16 tapers downwardly forwardly, but actually it is the downward taper inwardly, toward the longitudinal center of the vehicle, rather than forwardly which is important because it is desired that the ski (or other drag device) contact the sliding medium throughout the whole effective bottom area of the drag device when the vehicle is tilted in the direction of such device. Numerous modifications are possible and instead of skis, bent up drag devices might be used at the rear of the vehicle, the main idea being that the drag device will contact the sliding medium with an appreciable surface when the vehicle is tilted in its direction.

With any of the arrangements it is a characteristic of the present invention that, during vehicle travel in the direction of the central runner and subsequently lateral tilting to engage one or the other of the drag devices, the drag device will provide more resistance to sliding than the resistance provided by the central runner, thus causing turns while preventing spilling. This effect can be greatly aided by the shape of the central pan from which the central runner depends. When the vehicle is tilted, this central pan can act as a cam, elevating the central runner from the sliding medium and eliminating the possibility of turn resistance from central runner. In effect, then, the front of the pan skids around on the front curved portion (of bilge rather than keel) when a side mounted drag device engages the medium on which the vehicle is traveling.

And an outstanding characteristic shown in the drawings is that the drag devices may have bottom sliding medium contacting surfaces lying in planes which are angled so that, if extended, they will intersect a plane defined by the bottom surface of the central runner.

Of course, any turned up front end ski or skate might be expected to provide some turning force (if its mate is not active) but a ski which is angled in accordance with the disclosure in FIGS. 1-4 and 7 or a simple bracket as shown in FIG. 5, will provide a great deal more turning force and thus a more rapid and more controllable turn and, at least with the construction of FIGS. 1-4, the sled is much safer than center plus outboard runner sleds heretofore known first because there will be little tendency for any outrigger ski to dig in and flip the vehicle, and secondly because it is not necessary to laterally tilt the vehicle so far for a predetermined turn and this minimizes the chance of upset.

In FIG. 8, the exploded view shows one form of drag device (similar to each ski 16 in FIGS. 1, 2 and 4) where a sheet metal central portion 100 is provided at each end with top flanges 101 (for fastening as to a platform) and provided at each side with side flanges 102 useful for fastening on side plates 103 which, after assembly, can

serve to keep water, snow or ice out of the "inside" of the sub-combination. Water is not so likely to enter from above (through hand holes 33, 34 in FIG. 1) because the platform 10 usually planes above the water.

While I have illustrated and described particular embodiments, various modifications may obviously be made without departing from the true spirit and scope of the invention which is intended to be defined by the appended claims taken with all reasonable equivalents.

10. I claim:

1. A vehicle having a platform portion, a depending central runner secured to said platform portion and having at least one bottom surface, and a pair of drag devices affixed to the platform and oppositely disposed one on either side of said central runner, said drag devices each having a bottom surface lying in a plane which is elevated relative to the bottom surface of the central runner, and said drag devices each configured and arranged at an angle with respect to a fore and aft line through the central runner to provide, during vehicle travel in the longitudinal direction of the central runner and lateral tilting to engage with the supporting medium one or the other of the drag devices, more resistance to sliding than the resistance provided by said central runner.

2. A vehicle as in claim 1 further characterized by the drag devices being brackets having ends which are angled downward with respect to the platform portion and having bottoms which are corrugated at an angle with respect to a line extending fore and aft of the vehicle.

3. A vehicle as in claim 1 further characterized by the central runner being formed as a pan whereby to reduce manufacturing costs, to provide buoyancy when the device is used in water, and to provide a strong structure with a minimum amount of material.

4. A vehicle as in claim 1 further characterized by the platform portion comprising a pair of plywood wings each flaring upward from a longitudinal axis through the central runner.

5. A sled or ski runner having a front and a back and a surface which adjacent the front is convex when viewed from the bottom to provide outboard rounded edges in the fore portion with this configuration changing aft into a concave surface as viewed from the bottom to provide sharp outboard edges adjacent the rear of the device, the front portion also having a small central runner having sharp edges, whereby the sharp edges front and back may prevent side skids except when the runner is laterally tilted to remove the small central runner from engagement with a sliding medium and instead engage said sliding medium with a rounded edge, adjacent the front for turning.

6. A vehicle for use on a sliding medium, said vehicle having a triangular outline in plan view and comprising a platform portion for receiving a load during turning and a depending central portion formed as a pan open at the top, the platform extending from each side of but not over the central pan so that the pan is a depression to accommodate a rider while the platform extending to either side provides wings to which the rider may shift weight for making turns, the platform wing portions having drag devices located on opposite sides of the pan and depending from the platform wings, said drag devices having bottom surfaces which except during such weight shifting and turning are elevated with respect to the bottom surface of the pan.

7. A vehicle as in claim 5 further characterized by the central pan itself having a depending central runner having a bottom surface and the planes in which the bottom surfaces of the drag devices fall being angled to the plane of the bottom surface of the central runner so that said drag device bottom planes, if extended, will intersect the plane of the bottom surface of the central runner, whereby to provide maximum area of drag device contact with sliding medium during turning.

8. A vehicle for use as a sled and the like having a

platform portion and depending from said platform portion a longitudinally extending central pan the width of which is appreciably less than the width of the platform portion, a central runner depending from the central pan and extending longitudinally with the parts configured and arranged so that the central pan may act as a cam eliminating the possibility of turn resistance from the central runner when the vehicle is tilted by elevating the central runner from the supporting medium and further characterized by the pan having curved edges at least at the fore part of the vehicle, the platform having drag devices located on opposite sides of the pan whereby the front of the pan may skid around on a front curved edge thereof when the drag device is engaged.

9. A vehicle having a platform, a downwardly depending central runner affixed to said platform, a pair of downwardly depending devices affixed to the platform one on each side of the central runner and each having a bottom surface formed of corrugations angled with respect

to a line running fore and aft through the central runner, the bottoms of said corrugations lying in a plane which is elevated with respect to the bottom of the central runner.
